DISPENSING AND CLOSING DEVICE FOR TABLETS, PILLS, AND THE LIKE

Paul Kreiten, Cologne-on-the-Rhine, Germany

Application September 1, 1937, Serial No. 162,049
In Germany August 28, 1936

7 Claims. (Cl. 206—42)

This invention relates to a dispensing and closing device for articles such as tablets, pills and the like to be removed singly through a dispensing aperture in the upper surface of the lid for manipulation with one hand, in which a flat slide controlling the interior of the container cooperates with means adapted to temporarily separate the interior of the container from the dispensing chamber, so that by one movement of the slide uncovering the dispensing aperture also a shutting-off of the dispensing chamber from the remaining spaces of the container is effected.

In known arrangements of this type a rotating slide is used as a flat slide, and a certain dependency of this movement on the shape of the container has to be taken into account, that it is either a circular or semi-circular shape has to be given to the container, this being often undesirable or difficult for the storing of the tablets in such a manner that they correctly fill the interior of the container and that they properly utilise the space at disposal. The manufacturing of the only semi-circular containers causes extraordinary difficulties owing to the different material displacement during the pressing so that such semi-circular containers are very seldom produced.

The known construction of the slide as rotary slide and the adaptation of the shape of the container to the path of movement of the slide have further the inconvenience, that certain apertures in the wall of the container, for instance the slit for the shaft or neck of the knob serving as handle for the flat slide, remain uncovered when the dispensing chamber is shut from the remaining space in the container, and that during the moving of the slide it cannot be avoided that the articles to be dispensed are clamped, broken or otherwise damaged as they bear directly against the slide face. Owing to the irregular path along which the slide is moved, the locking stop for shutting off the dispensing chamber from the other space in the container can not find a way between the adjoining edges of the tablets so that it will be disarranged, and the even chambers that the slide strikes against such points of the circumference of the tablets, at which the shock is directed accurately towards the centre of the tablet. The tablets placed in the same direction in front of the tablet to be dispensed will then act as stationary abutment.

All these inconveniences are obviated according to the invention if the shape and position

of the slide are such that, as easily exchangeable flat insert movable in straight line, and cooperates with locking means which serve also as abutments so that the dispensing chamber can be temporarily shut off from the other space in the container without, however, restricting the number of tablets and the length of the rows of tablets stored in the container.

An embodiment of the invention consisting of a dispensing and closing device for a rectangular box adapted to contain tablets, is shown by way of example in the accompanying drawings, in which

Fig. 1 shows in top plan view of the dispensing box.

Fig. 1a is a longitudinal section through the whole box on line A—B of Fig. 1.

Fig. 2 shows in bottom plan view the lid of the box.

Fig. 2a is a longitudinal section on line C—D of Fig. 2.

Fig. 3 shows in bottom plan view the flat slide.

Fig. 3a is a longitudinal section on line E—F of Fig. 3.

Fig. 4 shows a bottom plan view of an insert the bent down edge of which forms a frame which serves as bearing surface for the lid and bottom of the box.

Fig. 4a is a longitudinal section on line G—H of Fig. 4.

Fig. 4b is a cross section on line J—K of Fig. 4.

Fig. 5 shows in top plan view a sheet of paper placed on the bottom of the box.

Fig. 5a is a cross section on line L—M of Fig. 5.

Fig. 6 shows on larger scale a cross section through the filled box on line N—O of Fig. 1.

Fig. 7 shows in elevation the box with bottom removed and the dispensing aperture shut off and in the position which it assumes during a shaking movement obliquely in downward direction.

Fig. 8 is a similar view of the box as shown in Fig. 7, a tablet being dispensed after the dispensing aperture has been liberated.

The box consists of a box-shaped lid 1 having a slit-like aperture 3 and of a box-shaped bottom 5, both parts being of a rectangular shape and having each a set-off rim. A slidable plate 2 in the lid has a knob 2a projecting through slot 3. An insert 6 with downwardly bent edge forming a stiff frame is inserted into the bottom part 5, and a paper sheet 14 is loosely inserted between the upper side of the bottom part and the tablets 16 in this bottom part. The insert sheet 14 may

be glued on the bottom at one or several points. The slide 2 is covered, as shown in Figs. 1, 1a and 6 when the lid is on top, on the one hand by the inner surface of the lid and on the other hand by the outer surface of the insert 6 and securely held in its position. The dimensions of the dispensing slot 3 and of the knob 2a are such that the surface of the knob projects only very slightly above the plane of the outer side of lid 3, but 10 presents nevertheless a sufficiently large surface for the thumb of a hand in order that the slide may be moved in a straight line from one extreme position to the other extreme position in slit 3.

During the movements of the slide the space 15 6b in which the tablets are stored is continually shut off from the outer air so that neither bacillæ nor dust have access to the store room. The lid 1 and bottom 5 may further be secured in their mutual position by any suitable means or in any 20 other suitable manner.

Tablets 16 are distributed in the bottom part 5 under the insert 6 so that all rows of tablets either in longitudinal or transverse direction contain, if the box is completely filled, a uniform 25 number of tablets without being hindered by inwardly projecting flaps 7, 8, 9 and 12 arranged around a cut out portion 6a in the insert 6. The flaps 7, 8, 9 and 12 may either be soldered or welded on the upper surface of the insert 6. They 30 might, however, be formed by downwardly bent tongues cut out of the insert 6.

A flap 13 cut out of slide 2 is bent inwards and projects through the cut out portion 6a. This flap 13 is in the same direction and stands 35 just at the side of flap 12 when the box is in the position shown in Fig. 7 further corresponding to the final position of the short jerk-like shaking-position exerted upon the box in the direction of the arrow 17. In this position of the flaps 12 40 and 13 or of slide 2 relative to the parts 1 and 5 of the box, the dispensing chamber situated in one of the corners of lid 1 and corresponding with the dispensing opening 4 in lid 1, is not shut off from the path of movement of the tablets 45 in space 6b indicated by the arrow 17 in Figs. 7 and 8, so that for instance the tablet 1 can unhindered pass from the space 6b into the dispensing chamber 6a.

The movement of the next following tablet 2 50 for passing into the entrance to the dispensing chamber 6a situated between the edges of the flaps 9 and 12, is already prepared either by a guide flap 10 alone or by this guide flap 10 and a second guide flap 11 so that the second tablet 55 first comes to bear against the flaps 9 and 10, a small portion of its circumference penetrating already into the dispensing chamber 6a which is occupied by the tablet 1, whereas the next following movement of the slide which at the same 60 time liberates the dispensing aperture 4 as shown in Fig. 8, this tablet 2 follows the tablet 1 dropping out of the box, the tablet 2 bearing against flaps 10 and 13, so that flap 9 does no longer 65 serve as support. The same direction of movement is produced by the support 11 to the other tablets coming from 6b into the zone indicated by arrow 17, as soon as by a jerk-like movement exerted upon the box in the direction of the arrow 17, this box assumes the oblique position 70 illustrated in Figs. 7 and 8, in which position the shifting of the tablets takes place in space 6a and then the uncovering of the dispensing aperture 4 by the slide and subsequent dispensing of a tablet.

From the operation described results that, if 75

the box is full, the first of the tablets mounted in the bottom part of the box, covered by the insert 6 and which is to be dispensed, does not require any shaking movements in order to pass into the dispensing chamber, as it is located in the same 5 from the beginning, so that after the aperture 4 has been uncovered by pulling back the slide it moves from the position shown in Fig. 7 into the position shown in Fig. 8, the box has to be turned only so far that the aperture 4 is directed downward and the tablet 1 can drop out of the same into the open hand. If this has been done, slide 2 must first be pushed back from the position shown in Fig. 8 into the position shown in Fig. 7, whereupon the box is again shaken in 10 the direction of the arrow 17 in order that the next following tablet 2 can move at the place of the dispensed tablet 1.

It may, however, happen, especially unintentionally or by awkwardness, that a tablet which 20 has been brought into the position shown in the Fig. 7 tends to fall out of the path of movement in the direction of arrow 17 into an opposite direction if the box is held incorrectly. To prevent this, the tablets 16 may be covered by a sheet 14 25 of paper or other suitable material, which as shown in Fig. 6 is either loosely inserted between bottom and tablets or be stuck at one or several points on this bottom. The paper sheet 14 has at that corner which registers with the dispensing 30 chamber 6a and with the dispensing aperture 4a a portion 14a cut out in the approximate shape of a quarter of a circle and at the side of the same an incision 14b is made so that between this incision and the cut out portion a tongue 15 35 is formed which is downwardly bent as shown in Figs. 5a and 6.

This tongue 15 bears with its end against the circumference of the tablet located in the dispensing chamber 6a. This effect has been illustrated in Fig. 7 in that a zone slightly overlapping and limiting the dispensing chamber is hatched, the hatching indicating a portion of a paper sheet 40 14.

It is evident, that, if the box is held in opposite 45 direction to the direction of the arrow 17, the tongue 15 must prevent the tablet 1 from being pushed out of the dispensing chamber 6a.

I claim:—

1. A receptacle for round bodies, especially 50 tablets, comprising in combination a bottom plate of substantially rectangular shape with rounded corners, a continuous wall projecting upwards at right angles from said bottom plate, an insert corresponding to the internal shape of said wall and 55 having an aperture at one of its corners larger than the diameter of the round bodies, a downwardly directed flange all round the periphery of said insert engaging at its lower edge in said wall and forming with said bottom plate a magazine 60 for the round bodies, a top plate corresponding in shape to said lower plate and having a slot and an aperture slightly larger than the diameter of the round bodies and registering with the aperture in said insert, a continuous wall extending downwards at right angles from the periphery of said 65 top plate and engaging the upper end of said flange, a flat slide shiftable between said insert and said top plate and covering the slot in said top plate in every position, and a knob on the upper side of said slide and extending through the slot in said top plate to shift said slide relatively to said top plate to open and close the aperture therein.

2. A receptacle for round bodies especially

tablets, comprising in combination a bottom plate of substantially rectangular shape with rounded corners, a continuous wall projecting upwards at right angles from said bottom plate, an insert corresponding to the internal shape of said wall and having an aperture at one of its corners larger than the diameter of the round bodies, a downwardly directed flange all round the periphery of said insert engaging at its lower edge in said wall and forming with said bottom plate a magazine for the round bodies, a top plate corresponding in shape to said lower plate and having a slot and an aperture slightly larger than the diameter of the round bodies and registering with the aperture in said insert, a continuous wall extending downwards at right angles from the periphery of said top plate and engaging the upper end of said flange, a flat slide shiftable between said insert and said top plate and covering the slot in said top plate in every position, a knob on the upper side of said slide and extending through the slot in said top plate to shift said slide relatively to said top plate to open and close the aperture therein, and several projections at the edges of the aperture in said insert extending into the magazine and restricting the area thereof only to an inappreciable extent.

3. A receptacle for round bodies especially tablets, comprising in combination a bottom plate of substantially rectangular shape with rounded corners, a continuous wall projecting upwards at right angles from said bottom plate, an insert corresponding to the internal shape of said wall and having an aperture at one of its corners larger than the diameter of the round bodies, a downwardly directed flange all round the periphery of said insert engaging at its lower edge in said wall and forming with said bottom plate a magazine for the round bodies, a top plate corresponding in shape to said lower plate and having a slot and an aperture slightly larger than the diameter of the round bodies and registering with the aperture in said insert, a continuous wall extending downwards at right angles from the periphery of said top plate and engaging the upper end of said flange, a flat slide shiftable between said insert and said top plate and covering the slot in said top plate in every position, a knob on the upper side of said slide and extending through the slot in said top plate to shift said slide relatively to said top plate to open and close the aperture therein, and flaps extending from the edges of the aperture in said insert into the magazine.

4. A receptacle for round bodies especially tablets, comprising in combination a bottom plate of substantially rectangular shape with rounded corners, a continuous wall projecting upwards at right angles from said bottom plate, an insert corresponding to the internal shape of said wall and having an aperture at one of its corners larger than the diameter of the round bodies, a downwardly directed flange all round the periphery of said insert engaging at its lower edge in said wall and forming with said bottom plate a magazine for the round bodies, a top plate corresponding in shape to said lower plate and having a slot and an aperture slightly larger than the diameter of the round bodies and registering with the aperture in said insert, a continuous wall extending downwards at right angles from the periphery of said top plate and engaging the upper end of said flange, a flat slide shiftable between said insert and said top plate and covering the slot in said top plate in every position,

a knob on the upper side of said slide and extending through the slot in said top plate to shift said slide relatively to said top plate to open and close the aperture therein, and flaps extending from the edges of the aperture in said insert into the magazine, and spaced apart a distance slightly greater than the diameter of said round bodies.

5. A receptacle for round bodies, especially tablets, comprising in combination a bottom plate of substantially rectangular shape with rounded corners, a continuous wall projecting upwards at right angles from said bottom plate, an insert corresponding to the internal shape of said wall and having an aperture at one of its corners larger than the diameter of the round bodies, a downwardly directed flange all round the periphery of said insert engaging at its lower edge in said wall and forming with said bottom plate a magazine for the round bodies, a top plate corresponding in shape to said lower plate and having a slot and an aperture slightly larger than the diameter of the round bodies and registering with the aperture in said insert, a continuous wall extending downwards at right angles from the periphery of said top plate and engaging the upper end of said flange, a flat slide shiftable between said insert and said top plate and covering the slot in said top plate in every position, a knob on the upper side of said slide and extending through the slot in said top plate to shift said slide relatively to said top plate to open and close the aperture therein, and several projections at the edges of the aperture in said insert extending into the magazine and restricting the area thereof only to an inappreciable extent.

6. A receptacle for round bodies, especially tablets, comprising in combination a bottom plate of substantially rectangular shape with rounded corners, a continuous wall projecting upwards at

right angles from said bottom plate, an insert corresponding to the internal shape of said wall and having an aperture at one of its corners larger than the diameter of the round bodies, a downwardly directed flange all round the periphery of said insert engaging at its lower edge in said wall and forming with said bottom plate a magazine for the round bodies, a top plate corresponding in shape to said lower plate and having a slot and an aperture slightly larger than the diameter of the round bodies and registering with the aperture in said insert, a continuous wall extending downwards at right angles from the periphery of said top plate and engaging the upper end of said flange, a flat slide shiftable between said insert and said top plate and covering the slot in said top plate in every position, a knob on the upper side of said slide and extending through the slot in said top plate to shift said slide relatively to said top plate to open and close the aperture therein, and a flap extending into the magazine at the edge of said slide adjacent the dispensing aperture in said top plate and moving in a plane a short distance outside the periphery of the dispensing aperture in said top plate.

7. A receptacle for round bodies, especially tablets, comprising in combination a bottom plate of substantially rectangular shape with rounded corners, a continuous wall projecting upwards at

right angles from said bottom plate, an insert corresponding to the internal shape of said wall and having an aperture at one of its corners larger than the diameter of the round bodies and of unsymmetrical shape, a downwardly directed flange all round the periphery of said insert engaging at its lower edge in said wall and forming with said bottom plate a magazine for the round bodies, a top plate corresponding in shape to said 10 lower plate and having a slot and an aperture slightly larger than the diameter of the round bodies and registering with the aperture in said insert, a continuous wall extending downwards at right angles from the periphery of said top plate and engaging the upper end of said flange, a flat slide shiftable between said insert and said 15 top plate and covering the slot in said top plate

in every position, a knob on the upper side of said slide and extending through the slot in said top plate to shift said slide relatively to said top plate to open and close the aperture therein, flaps projecting into the magazine from the edges of the insert aperture, a flap extending into the magazine at the edge of said slide adjacent the dispensing aperture in said top plate and moving in a plane a short distance outside the periphery of the dispensing aperture in said top plate, a 10 paper insert on the inner side of said bottom plate having a cut away portion registering with the apertures in said first mentioned insert, and said top plate, and a tongue projecting upwards from said paper insert into the magazine opposite 15 these apertures.

PAUL KREITEN.
